Primary Examiner — George D Kirschbaum*Assistant Examiner* — Jennifer Watkins(74) *Attorney, Agent, or Firm* — Katherine M. Bond; Leech Tishman Fuscaldo & Lampi(57) **CLAIM**

The ornamental design for an appendage protector, as shown and described.

DESCRIPTION

FIG. 1 is a perspective view of an appendage protector, showing my new design in condition of use;

FIG. 2 is a top plan view of the appendage protector in an open position;

FIG. 3 is a front elevation view of the appendage protector; and,

FIG. 4 is a bottom plan view of the appendage protector similar to FIG. 2 in an open position.

The human form shown in broken lines in FIG. 1 is for the purpose of illustrating environment that forms no part of the claimed design. The broken line on the appendage protector represents claimed stitching.
